UNITED STATES PATENT OFFICE

ALFRED DHOME, OF ST.-DENIS, FRANCE, ASSIGNOR TO SOCIETE ANONYME DES ETABLISSEMENTS DELAUNAY BELLEVILLE, OF ST.-DENIS, FRANCE, A FRENCH CORPORATION

BOILER WITH HIGH EVAPORATIVE CAPACITY

Application filed December 3, 1926, Serial No. 152,435, and in France December 17, 1925.

The present invention relates to water tube boilers and more particularly to a type of water tube steam boiler, which allows of obtaining very high rates of evaporation with great security, and is constituted by evaporative tubes provided with gills or ribs, said gills being more numerous and spaced more closely together as the tubes are more and more distant from the furnace and one series of the tube elements of the boiler being so located as to afford efficient protection to the refractory walls of the furnace.

It is known that the transmission of the heat of the combustion gases to the water in boilers is effected in three stages.

1. From the gases to the metal of the heating surface.
2. Through the metal.
3. From the metal to the water to be evaporated.

The transmissions 2 and 3 take place easily, owing to high coefficients. It is only the transmission 1, that is from the gases to the metal, which is difficult, the heat exchange coefficient being low.

In ordinary water tube boilers there is active transmission of heat primarily through the surfaces directly exposed to radiation from the furnace and secondarily through the material of the first rows of tubes, in respect of which the high temperature of the gases compensates for the lowness of the coefficient of transmission by convection. Evaporation subsequently diminishes quickly and in order to cool down the combustion gases sufficiently before they are discharged, it is necessary to make them pass through a great number of rows of tubes.

A fair result can only be obtained by means of certain devices, particularly by means of baffles constraining the gases to make several passages through the nest of tubes. Anyhow only a small increase is obtained of the mean rate of evaporation of the boiler and at the expense of a great increase in the activity of the first rows of tubes.

The boiler, which is the subject of the present invention, obtains high rates of evaporation owing to an improved distribu-

tion of heat absorbed by the various tubes. It has at the same time a high efficiency at the most diverse temperatures owing to the efficiency in the absorption of the heat of the gases.

In the accompanying drawing there is shown one construction of the boiler which is the subject of the invention, Fig. 1 being a cross section and Fig. 2 a longitudinal section. Fig. 3 shows in cross section a modified construction of the boiler.

This boiler of Figs. 1 and 2 consists substantially of a drum 1 and one or more tube elements placed side by side and connected with the drum 1, each element being constituted by two straight headers 2, to which are attached the evaporative tubes 3 by expanding, welding or any other method.

The evaporative tubes 3, or at least a part of them, are provided with metal gills, projections or ribs 4 made when casting or machining or attached by welding or any other means giving an intimate connection of the metal. The purpose of these ribs is to increase the metallic surface in contact with the gases, and thus to obtain a greater heat transmission than with the same tubes without ribs. By increasing the number and size of the gills in proportion to the cooling down of the gases it is possible to maintain a high rate of evaporation up to the last rows of tubes and nevertheless to obtain a very low discharge temperature of the gases, that is to say a high efficiency for the boiler.

Communicating tubes 5 connect the headers 2 with the drum 1 and permit the circulation of the water and the giving off of the steam. The headers 2 of the elements are if necessary slightly machined on their contact surfaces in order to obtain sealing for the gases.

A feed and depositing drum 6 connected with each element is also provided and allows of the easy removal of deposits and mud at the same time as a practical feed.

The great efficiency of the transmission obtained enables several interesting arrangements to be realized. In the first place, it can be arranged that the gases traverse

only a reduced number of rows of tubes, in consequence baffles may be dispensed with and only a single passage for the gases is thus left. The elimination of baffles allows 5 of the easy installation of powerful cleaning apparatus the utility of which is well known.

In the second place such a boiler with a 10 direct path for the gases and a small number of rows of tubes offers very little resistance to the passage of the gases. This allows of high speed of circulation, which are themselves favourable to the transmission of heat.

15 Finally the headers 2 of one and the same element may be arranged at an angle to each other thus allowing of maintaining high rates of passage for the gases, in spite of their cooling down. This arrangement 20 would have furthermore the advantage of shortening the communicating pipes and of thus facilitating a good circulation in the boiler. The speed of the gases can also be increased by bringing the tubes nearer together.

25 This type of boiler may also comprise two or more drums 1 if it is wished to increase the reserve of water. With this object evaporative tubes 3 of comparatively large diameter can be used whilst maintaining a high rate of evaporation.

30 Furthermore, several series of headers 2 can be attached to the drums 1. One of the additional series of headers can be utilized to protect the furnace walls, whilst at the same time the corresponding evaporative tubes can serve for increasing the activity of the boiler. For this purpose it is sufficient to place the evaporative tubes in question in 35 communication with the drum 1 and to distribute them at the desired level by causing them to pass in front of the refractory walls or inside them in order to protect them from the action of the fire.

40 45 By way of example there are shown in Fig. 3 the position of the additional headers 2' and tubes 3' protecting the walls, the normal elements of the boiler being constituted by the headers 2 and tubes 3 shown in full lines. The tubes 3' may be smooth 50 or also provided with ribs or gills. Pipes 5' connect the headers 2', 3' with the drum 1 thereby placing the evaporative tubes in communication with the drum independently 55 of the tubes 3.

Claim:

60 A water tube boiler with high evaporative capacity, comprising in combination substantially parallel evaporation tubes arranged in parallel groups, headers connected to the ends of said tubes, arranged parallel to the general flow of gases escaping from the furnace, an upper drum connected to 65 said headers, the headers to which are connected the ends of the tubes converging so

as to form an acute angle towards said upper drum, whereby the lengths of the said tubes are decreased towards said drum, means for feeding water to the headers at the lower end and transverse heat transmitting fins provided on said tubes and located more closely together as said tubes are more and more distant from the furnace, whereby the hot gases flowing through the boiler effect only one travel in the same general direction approximately parallel with the 70 surface of said fins.

75 In testimony whereof I affix my signature.

ALFRED DHOME.
